UNITED STATES PATENT OFFICE.

FRANK KEMETHER, OF GLASGOW, DELAWARE.

DESIGN FOR A HOOK.

SPECIFICATION forming part of Design No. 33,551, dated November 13, 1900.

Application filed September 8, 1900. Serial No. 29,472. Term of patent 14 years.

To all whom it may concern:

Be it known that I, FRANK KEMETHER, a citizen of the United States, and a resident of Glasgow, in the county of New Castle and State of Delaware, have invented and produced a new and original Design for a Hook, of which the following is a full, clear, and exact description.

Reference is to be had to the accompanying drawing, forming a part of this specification, in which the figure is a perspective view of a hook, showing my design.

The invention relates to hooks employed for holding the three-horse tree temporarily in position on the tongue of a grain-binder to allow convenient removal or displacement of the tree.

The leading feature of the design consists of the configuration of the hook made the subject of the accompanying illustration.

The design in its entirety consists of a straight shank A, terminating at one end in an open hook B and at the other end in a straight arm C, bent approximately at a right angle to the shank and projecting in an opposite direction to that in which the end of the hook projects. 25

Having thus fully described my invention, I claim as new and desire to secure by Letters Patent—

The design for a hook, as herein shown and described.

In testimony whereof I have signed my name to this specification in the presence of two subscribing witnesses.

FRANK KEMETHER.
